(57) **CLAIM**

The ornamental design for a desk, as shown and described.

DESCRIPTION

FIG. 1 is a left front perspective view of a desk showing my new design;

FIG. 2 is a front elevational view thereof;

FIG. 3 is a rear elevational view thereof;

FIG. 4 is an end elevational view, the opposite end being a mirror image thereof;

FIG. 5 is a top view thereof; and,

FIG. 6 is a second rear view, omitting the ornamentation located on the front edge for clarity thereof.

The broken lines are for environmental purposes only and form no part of the claimed design.

The bottom view of the table is not shown and forms no part of the claimed design.

1 Claim, 6 Drawing Sheets
